UNITED STATES PATENT OFFICE.

MORRIS W. POOL, OF NEW YORK, N. Y., ASSIGNOR TO REMINGTON TYPEWRITER COMPANY, OF ILLION, NEW YORK, A CORPORATION OF NEW YORK.

TYPEWRITING MACHINE.

Application filed June 25, 1921. Serial No. 480,393.

To all whom it may concern:

Be it known that I, MORRIS W. Pool, citizen of the United States, and resident of the borough of Brooklyn, city of New York, in the county of Kings and State of New York, have invented certain new and useful Improvements in Typewriting Machines, of which the following is a specification.

10 My present invention relates to typewriting machines and its general object is to provide a machine which is particularly adapted to work of the character known as collating and also to fan-fold billing work, 15 as well as ordinary work.

To the above and other ends the invention consists in the features of construction, combinations of devices and arrangements of parts hereinafter described and particularly pointed out in the claims.

Specifically, the present improvements relate to a modification of the invention disclosed in my application Sr. No. 470,818, filed May 19, 1921. In said application provision is made for moving the work carrying element relatively to the printing instrumentalities in order to provide sufficient room to facilitate the adjustments of the work sheets. By my present invention a space or gap for this purpose is provided by bodily moving the printing instrumentalities as a unit away from the paper holder or carrying element.

In the accompanying drawings which illustrate the preferred form of the invention,

Figure 1 is a fragmentary end elevation of a typewriting machine embodying the invention, parts being broken away for the sake of clearness and only such parts being illustrated as are necessary to a complete understanding of the invention.

Figure 2 is a vertical sectional view taken on a plane indicated by the dotted line 1—1 in Fig. 1 and looking forward in the direction of the arrow at said line.

Figure 3 is a fragmentary horizontal sectional view taken on a plane indicated by the dotted line 2—2 in Fig. 1 and looking downward, said Fig. 3 being drawn to a larger scale, however, than Fig. 1.

Figure 4 is a vertical sectional view taken substantially on a plane indicated by the dotted line 3—3 in Fig. 1 and looking rear-

ward in the direction of the arrow at said line.

Figure 5 is a perspective view of a part hereinafter described as a bracket or supporting member.

Figure 6 is a fragmentary perspective view of a modified construction.

As shown in Figures 1, 2 and 3 there is provided a base or supporting member 1 which may be of wood or other suitable material and which supports a track or guide member comprising a horizontal plate-like base portion 2 and upright side portions or bars 3, said member being cut out as indicated at 4 for the sake of lightness and being secured in any suitable way to the base 1 as by screws 5. Each bar 3 is provided with cutouts or openings indicated at 6 near its front and rear, said openings being generally rectangular but formed at their lower sides with depressions or seats 7, the depressions being connected by a straight horizontal portion 8 which together with the depressions 7 constitutes a runway or trackway. Co-operative with each trackway 7, 8 is a grooved roller 9 bearing on a screw pin 10 which is threaded into a block 11 which in turn is secured as by rivets 12 to a T-shaped bracket 13, the head whereof is in turn fixed by screws 14 to the typewriting machine proper. In the present instance the typewriting machine preferably is constituted by two separate parts or unitary structures, one, the printing or type bar unit, and the other the paper carrying unit.

The type carrying unitary structure is housed in and supported on a frame which comprises a base 15, side plates 16 secured to the base, and a top plate 17 surmounting the side plates, the three portions being suitably secured together to provide a rigid frame or housing. The base portion 15

which may be of cast metal and U-shaped has the T-shaped brackets 13 secured to the inner faces of its side walls by the screws 14 so that said brackets and the pivotal supports 10 of the wheels or rollers 9 are rigid with the type carrying frame 15, 16, 17, said frame and the parts supported on it being thus mounted to roll on the stationary trackways or edges 7, 8, as when pulled or pushed by the operator. The construction is such

that the type carrying frame has a limited fore-and-aft movement on the trackway, the

vertical end portion of the opening 6 constituting stops which co-operate with the wheels 9 to limit such movements, and the stops being so related to the depressions 7 that the wheels are seated in the depressions when thus arrested. To insure the retention of the wheels in their seats or depressions 7, until it is desired to shift the type carrying unit from one of its predetermined positions to the other, spring detent devices 18 may be provided to co-operate with the wheels 9 to exert sufficient pressure thereon to prevent their accidental unseating from the depressions 7. The type carrying unit 15 contains and supports not only the type bar system but also the ribbon mechanism, parts of the escapement and tabulating mechanism, as well as other appurtenances, all of which are preferably of the general construction disclosed in my aforesaid application Serial No. 470,818 and which for present purposes require only a brief description. The type bars 19 constituting the aforesaid type bar system are of the front strike variety, the set or system of type bars being arranged in an arc of a circle and pivotally mounted on a pivot wire 20 which is supported on an inclined segment or support 21 fixed to the side plates 16. The type bars 30 are arranged in guide slots 22 formed in said segment and are normally supported near their free ends by a curved rest 23 which is supported from the top plate 17. Each type bar is formed with a cam slot 24 by which it is connected with a train of actuating devices comprising a pin 25 engaging in said slot and projecting laterally from the upwardly extending arm 26 of a bell crank lever which further comprises a short arm 27. Said bell crank is pivoted on a pivot wire 28 common to all of the bell cranks and mounted on a stationary support 29 carried by the frame member 15, 16, 17 and provided with slots 30 wherein the bell cranks are received. Links 31 connect the short arms 27 with key levers 32, the system of key levers being pivoted in the rear of the base portion 15 on a common pivotal support 33, each lever having a key 34 providing a keyboard at the front of the frame portion 15. The type bars 19 are each furnished with a single type 35 but it is to be understood that if desired a plurality of types on each type bar may be employed in association with suitable case shifting mechanism.

The types 35 are adapted to print through the printing portion of a ribbon which is preferably controlled by vibrating mechanism and fed by ribbon feeding mechanism of the general character referred to in my prior application, the ribbon feeding mechanism comprising a ribbon driving shaft 36 which is horizontally arranged and is rotatable from the spring drum or motor

mechanism of the machine through a train of devices comprising a beveled pinion 37 on said shaft 36 which pinion meshes with a beveled pinion 38 rigid with a ratchet wheel 39 that is impelled by a spring pressed pawl 40. The ribbon driving shaft 36 may be supported from the sides of the machine frame. The pinion 38 and ratchet wheel 39 are preferably mounted on a vertical shaft 41 which is supported on a bracket member designated as a whole by the numeral 42 and most clearly shown in Fig. 5. Said bracket member preferably is made of a single piece of metal cut out and bent to the shape shown. The shaft 41 bears at 80 its upper end in a bearing opening indicated at 43 formed in the fore-and-aft central portion 44 of said bracket. Lateral branches 45 are extended from said central portion and bent to provide a rectangular frame 85 part, the ends of which are suitably connected. A bearing or thrust block 46 is fixed to the lower side of said rectangular frame part as by screws 46^a, the lower end of the shaft 41 bearing in said thrust block 90 46. Behind and parallel with the branches 45 a pair or lateral branches or arms 47 extend from the central portion 44, these branches 47 having downwardly bent end portions 48 which terminate in inwardly 95 extending ears 49 that are secured by screws 50 to a channel-like cross bar 51 arranged transversely of the base and secured at its ends by screws 52 to thickened portions 100 15^a of the base, the screws 52 being threaded up through the central web of the channel into tapped holes in said thickened portions 15^a, as clearly shown in Fig. 2. The bracket member 42 is thus secured to the base 15 and provides a support which is 105 rigid with said base. The front end of the central portion 44 is inclined downward and forward and is secured by a screw 53 to the support 29, thus additionally securing the bracket 42. The bracket 42 also 110 provides a support for a motor or spring drum mechanism which comprises a drum or casing 54 and a large beveled gear wheel 55 arranged above the casing 54, said casing and said gear wheel being mounted on the 115 shaft 41 and being constantly urged in rotary direction by a main spring of ordinary construction housed within the casing 54. The pawl 40 is mounted on the top of the gear wheel 55 so as to co-operate with the ratchet wheel 39 to turn the latter during printing movements of the paper carriage. Constantly meshing with the horizontally arranged gear wheel 55 at its rear side is a vertically disposed beveled pinion 120 or smaller gear wheel 56 which is mounted near the rear end of a horizontally disposed shaft 57, said shaft extending forward and being supported on the bracket 42, a forward bearing 58 for said shaft being 125 130

formed in the block 46. The rear end portion of the shaft 57 is provided with a key 59 and the key portion of the shaft bears in a rotary bushing or sleeve 60, said bushing being cut out as indicated at 61 (Fig. 5) to accommodate the key portion of the shaft, the two parts having a slidable engagement and being adapted to rotate together. The bushing or sleeve 60 is formed 10 with a groove or circumferential depression 62 which bears in an opening formed at the lower end of an arm 44^a which is in effect a downward or angular extension of the central portion 44 of the bracket 42. The beveled pinion 56 is mounted on the shaft 57 so as to permit the shaft to slide through and relatively to said pinion, said pinion however being forced by the key 59 to participate in rotary movements of the shaft in 20 all positions of the latter. Fixed to the rear face of the beveled pinion as by rivets 63 is an escapement wheel 64 provided at its circumference with teeth 65 which co-operate with detent or dog devices to be 30 hereinafter described. The escapement wheel may be countersunk at its rear side to partially seat the bearing sleeve 60. The rear portion of the shaft 57 accommodates a two-part clutch, the forward clutch part 66 being keyed to the shaft by the key 59 so that it is always compelled to turn with said shaft. Said clutch part 66 is provided at its front side with a flange 67 and is constantly urged rearward along the shaft 57 40 by a forked leaf spring 68 which is secured at its upper end by a screw 69 to the bracket member 42, the lower or forked end of the spring loosely embracing the shaft 57 and pressing against the flange of the clutch part 66. The rear of said part 66 is provided with clutch teeth which normally mesh with corresponding clutch teeth formed at the front face of the second clutch part 70, said second clutch part being 50 formed integral with and providing the hub portion of a beveled gear wheel 71 which provides a connection with the traveling paper carrying element as hereinafter described. The clutch part 70, 71 may bear 60 on a reduced rear end portion of the shaft 57 which provides a shoulder on the shaft preventing forward displacement of said clutch part. A collar 72 pinned or otherwise secured to the shaft behind said clutch part prevents rearward displacement of the latter. The construction also prevents endwise movement of the shaft 57 when the clutch part is held. It will be understood that the bodily fore-and-aft movements to 70 which the frame 15, 16, 17 are subjected are participated in by the bracket member 42 and by the parts carried by said bracket member including the spring drum and its casing 54, the intermeshing gear wheels 55 and 56, the escapement wheel 64, the sleeve 60 and the clutch part 66, such of these parts as are mounted on the shaft 57 moving on and relatively to the shaft, which together with the gear wheel 71 will not affect it by such fore-and-aft movements. 75 Co-operative with the escapement wheel 64 is an anchor escapement member 73 provided with teeth or detents 74 and 75 which are adapted to co-operate with the teeth 65 of the wheel 64 at one side thereof. The anchor member 73 is provided with a hub portion 76 which fits over the rear end of a rock shaft 77, said shaft having as its rear bearing an inward projection 48^a from one of the bent portions 48. The hub 76 is provided with a key pin 76^a which engages in a longitudinal way or groove 77^a formed in the shaft 77, the construction insuring that the anchor member 73 shall participate in rotary movements of the shaft 77 while permitting endwise movements of the member 73 along the shaft. The forward end portion of said shaft 77 bears in a bearing opening indicated at 78 in the block 46. The shaft 77 projects forward through said block and its projecting end receives the hub portion 79 of a crank arm 80 which is secured to the shaft 77 by a pin 81 passing through the hub. The crank arm 80 projects horizontally outward or leftward and at its outer free end is connected by a depending link 82 with the free end of a crank arm 83 which is fixed to and extends forward from a rock shaft 84 arranged transversely of the base 15 and taking bearings at 90 the sides thereof. Said rock shaft is provided near its ends with forwardly extending crank arms 85 which are suitably fixed to said shaft and are slightly inclined downward therefrom, the free ends of said crank arms being connected by a cross bar 86 which underlies the key levers and is adapted to be operated by them when they are depressed, said cross bar acting as a universal bar for the escapement mechanism. It 100 will be understood that when one of the printing keys 34 is operated to cause its associate type bar 19 to print, the actuated key lever 32 will depress the universal bar 86, rocking the shaft 84 and swinging the crank arm 83 downward, such downward movement being transmitted through the link 82 to the crank arm 80 which will rock the shaft 77, causing the anchor member 73 to co-operate with the escapement wheel to afford a letter space feed movement of the carriage on the completion of the oscillatory movement of the anchor member, the impulse of the spring drum being transmitted to the shaft 57 through a train of connections comprising the gear wheels 55 and 56 and the key 59, and the movement of said shaft being transmitted to the carriage or the paper carrying element through the train of connections comprising the clutch 110 120 125 130

parts 66 and 70 and the gear wheel 71. From what has been said it will be understood that the ribbon vibrating and ribbon feeding mechanisms, together with the escapement mechanism, are mounted on the frame 15, 16, 17 so as to participate in its fore-and-aft movements on the track bars 3; that the ordinary functions of the ribbon vibrating mechanism are not interfered with, such 10 mechanism normally maintaining the printing portion of the ribbon below the printing point but at each type bar actuation operating to interpose the printing portion of the ribbon in the path of the actuated 15 type bar 19 so that said type bar is caused to print through said ribbon; and that the ribbon receives a feeding impulse or advance movement at each type bar actuation, due to impulses transmitted through the 20 gear wheel 55, pawl 40, ratchet wheel 39 and intermeshing pinions 38 and 37 to the ribbon driving shaft 36 and thence in alternation to the ribbon spools which are not shown herein but which are adapted to be connected 25 with the ribbon driving shaft in the manner more fully explained in my said prior application.

Referring next to the work carrying devices, as appears from Figs. 1 and 4, posts 30 87 rise from the sides of the plate-like base 2 at its rear, said posts supporting transversely extending parallel trackways 88 which are oppositely grooved to receive anti-friction rollers 89. The rollers 89 also 35 co-operate with a pair of oppositely grooved rails 90 which are part of the structure of the traveling carriage or work carrying element, said carriage further comprising uprights in the form of angle bars 91, the rails 40 90 providing cross bars connecting said uprights 91, and the whole constituting a rigid carriage frame. Secured to the front of this frame as by rivets 92 is a plate, table 45 or flat paper holder 93 providing an upright vertically disposed work-receiving plane surface which preferably is formed at its upper part with a transversely extending slot indicated at 94 for the accommodation of a rotary platen 95. Said platen may 50 be of ordinary construction and is arranged behind the flat paper holder or table 93 but projects forward through the opening or slotway 94 so that the front or printing face of the platen is substantially in the plane of said table which is also the printing plane of the paper. For the sake of clearness the extent of forward projection of the platen through the table is exaggerated in Fig. 1. The axle portions 96 of the 55 platen bear in the side portions of the angle bars or uprights 91 and at their ends are provided with the usual finger wheels or twirlers 97. Mounted on the right-hand platen axle 96 inside the side portion of the upright 91 is a line spacing ratchet

wheel 98 with which is adapted to cooperate a line spacing pawl 99 pivoted at 100 on a pawl carrier 101 which is loosely mounted on said platen axle. The pawl 99 is angularly shaped and the arm opposite 70 from its engaging portion or tooth has pivotally connected to it at 102 a link 103 which extends upward and at its upper end is pivotally connected at 104 to a crank arm 105 fixed to the rear end of a rock shaft 106. 75 Said rock shaft which bears in a bearing or housing 107 rigidly mounted on the right-hand angle bar 91, extends horizontally forward terminating in a downwardly extending handle or finger piece 106a. It will be 80 understood that when the shaft 106 is rocked by its handle it operates to swing down the crank arm 105, this motion being transmitted through the link 103 to the pawl 99 which is initially thrown into engagement 85 with the ratchet wheel 98, subsequently operating, as the pawl carrier 101 is rotated downward, to turn the ratchet wheel and communicate a line spacing rotary movement to the platen 95. Suitable detent devices (not shown) co-operate with the ratchet wheel to hold the platen against accidental turning movements. The handle 90 106a also serves as a convenient means for restoring the carriage from left to right 95 along its guide rails after the completion of a line of writing. Connections between the carriage and the carriage motor or spring mechanism of the machine are provided by an angular or beveled rack bar 108 which is 100 secured to the front face of the table 93 and extends transversely thereof, the inclined face of said rack bar being formed with teeth which co-operate with the teeth of the beveled gear wheel 71. The rack bar 108 and gear wheel 71 are maintained constantly engaged or intermeshed by means of an angle bar 109 which is secured to the top of the toothed bar 108 and has a downwardly extending portion which lies forward of the gear wheel 71 in such position as to prevent, in all positions of the carriage, a forward displacement of said gear wheel. The construction is such that the gear wheel cannot be displaced axially in 115 either direction. It will be perceived that the impulse of the spring drum will be transmitted through the shaft 57, gear wheel 71 and feed bar 108 to the carriage, and constantly tends to urge the carriage leftward 120 on its guide bars, permitting leftward step by step or letter feeding movements under the control of the escapement mechanism in the manner hereinbefore described.

Tabulating mechanism as in my prior application may be provided, said tabulating mechanism comprising a toothed tabulator bar 110 which is arranged at the lower end of the carriage, being secured to brackets 111 fixed to the carriage, said bar 110 ac- 125 130

commodating adjustable column stops 112 co-operating with one or more relatively stationary key controlled stops, which as hereinafter described effect also the release 5 of the carriage from its escapement devices. The carriage is adapted to be released not only by the tabulating mechanism but also by key controlling devices on the carriage, said devices comprising a cross bar 113 10 which is carried by angular arms 114 pivoted at 115 to the associate uprights 91 and adapted to vibrate to an extent determined by stops 116 projecting laterally from one of said uprights at opposite sides of the associate arm 114. The release bar 113 normally lies behind and just out of contact with the flange 67 of the clutch part 66, the arms 114 being adapted to be turned on their pivots to swing the release bar forward 20 against the flange 67 so as to overcome the spring 68 and slide the clutch part 66 forward on the shaft 57, disconnecting it from the gear wheel 71 which is thereby released from the control of the carriage escapement devices. The means for causing releasing movements of the bar 113 comprise a crank arm 117 concentric with, and rigidly connected to, one of the angular arms 114, said crank arm being connected with a 30 release key, not shown, by devices comprising a link 118.

The paper feeding and controlling devices include angular paper fingers arranged at the sides of the table 93 and each comprising an upright portion or paper finger proper 119 provided with a pressure roll 120 co-operative with the platen 95 near its ends and along the printing line. The paper fingers are provided with horizontal angular portions 121 which extend to the sides of the table 93 and thence are bent rearward at right-angles, providing side portions 122 outside the uprights 91. The forward portions of the parts 122 receive headed pivot screws 123 which are secured in angular brackets 124 fixed by screws 125 to the table 93. Draw springs 126 connected to the arms or parts 122 tend constantly to turn the paper finger members on their pivots 123 and maintain the pressure rolls 120 operatively against the platen or the paper thereon. The upright portions 119 of the paper finger members are punched to provide forwardly bent finger portions 119^a which serve 55 as convenient finger pieces for releasing the pressure rolls. Below the paper fingers there is provided a paper guide bar 127 which extends transversely of the table 93, said guide bar being mounted at its ends on angular arms 128 pivoted at 129 to the sides of the uprights 91, said arms 128 preferably having rearward extensions which are connected by links 130 with the paper finger members so that actuations of the keys or 60 finger pieces 119^a to release the pressure

rolls 120 will also throw the guide bar 127 forward away from the table 93, said table being thus cleared or left unobstructed substantially throughout its front surface, enabling the work sheets readily to be adjusted thereon. When separate work sheets are employed of the character illustrated in Fig. 1 and designated *a*, *b* and *c*, any of them may be dropped against the top horizontal portion of the bar 109 which serves as a convenient ledge or stop for the purpose. The upper ends of said sheets, after passing the printing point, may be guided by angular fingers 131 which are secured by screws 132 to the upper end portions of the uprights 91. 75

Co-operative with the tabulator column stops 112 is a tabulator frame stop which in the present instance comprises a tabulator key lever arm 133 provided with an ordinary key cap and stem at its front end, the rear end of said arm 133 being fixed to a rock shaft 134 near its right-hand end, said rock shaft bearing in the sides of the base 15. Fixed about centrally to said rock shaft and extending rearward therefrom is a tabulator stop lever arm 135, the free end whereof is adapted to co-operate with the column stops 112 though normally lying below the paths of said stops. When the tabulator key is depressed the lever arm 133 rocks the shaft 90 134 causing the arm 135 to swing upward and bringing the stop portion thereof into the paths of the stops 112. The operation of the tabulator lever member 133, 135 also effects the release of the traveling carriage 100 from its escapement mechanism preferably by a train of connections which throw the anchor member 73 temporarily out of engagement with the escapement wheel 64. Said train may comprise a crank arm 136 fixed to the rock shaft 134 to the left of the arm 135 and extending upward from said rock shaft. A link 136^a connects the crank arm 136 with the downwardly inclined arm of an angular lever 137, the other or upwardly extending arm whereof is bifurcated or forked, the bifurcated portions 138 engaging loosely in a circumferential groove 76^b formed in the hub of the anchor member 73. The angular lever 137 is pivoted at 137^a 115 to an angular bracket 51^a secured to the top of the cross bar 51. The depression of the tabulator key rocks the shaft 134, as has been stated, causing the crank arms 136 to swing forward, this movement being transmitted through the link 136^a to the angular lever 137, compelling the forked or bifurcated end portion 138 thereof to swing rearward which movement results in the sliding 120 of the anchor member 73 rearward along its supporting shaft carrying the member 73 out of engagement with the escapement wheel 64. The parts are timed so that the consequent release of the carriage from the control of its escapement mechanism and its 130

leftward movement under the impulse of the spring drum mechanism does not occur until the tabulator lever arm 135 has swung up into the path of the stops 112, the result 5 being that the run of the carriage will be ended by co-operation of the actuated stop lever 133, 135 and the proximate column stop 112. When the tabulator key is released the parts including the anchor member 10 73 will be restored to normal position by the usual or suitable springs. Independent movement of the anchor member 73 lengthwise of the shaft 77 may be limited by contact of the key device 76^a with the 15 ends of the slot 77^a, said key device preferably being in the form of a pin driven through the hub 76 to a sufficient extent to project part-way into the groove 77^a.

In collating work where it is desired relatively to adjust a plurality of work sheets, such as the comparatively long and wide record sheet *c*, the shorter bill sheet *a* and the interposed carbon *b* shown in the drawing, the operator need only pull forward or 20 toward himself the type bar supporting frame or unitary structure comprising the frame 15, 16, 17 and the parts mounted thereon from the full line position to the dotted line position of Fig. 1. This movement of the type bars and their supporting frame is in a direction substantially at right-angles or perpendicular to the writing or printing plane of the paper and also at right-angles to the path in which the 25 carriage moves transversely on its fixed guideways. The result is that the printing and paper carrying units are spread apart or separated so that a gap or space is provided between them sufficient to enable the 30 work sheets to be conveniently manipulated and adjusted on the collating table or plate 93. Said plate, of course, should be preliminarily cleared by releasing the paper controlling devices. When the unitary 35 structure is pulled or slid forward, as has been described, by the hand of the operator applied to any convenient part thereof, the bracket 42 will, of course, move with it, and the parts mounted or carried by said 40 bracket will participate in such movement, with the exception of the shaft 57 which will remain stationary, held by the gear 71, and will maintain its connection with the carriage, the key 59 permitting the gear 45 wheel 56 and the escapement wheel 64 to slide forward along the shaft 57 without obstruction. When the type bar unitary structure has been moved bodily forward, as has been described, it will be retained 50 in the abnormal position with the wheels 9 accommodated in the forward seats 7 by its own weight assisted if need be by the 55 detent devices 18, so that both hands of the operator will be free to effect the necessary paper adjustments and manipulations. 60

After the work sheets have been collated or adjusted as desired, the paper controlling devices are released so as to hold the sheets in proper relationship and then the type bar structure is pushed back to normal position, that is, to the full line position in Fig. 1, after which the writing may be proceeded with until the desired entries have been completed.

A modified construction adapting the invention to use with fan-fold sheets is illustrated in Fig. 6 wherein the fan-fold sheet is designated by the character *d*. In the modified construction the plate-like bar 2 is formed at its sides with lateral extensions 139 from which rise posts 140 to which are secured extended grooved trackways 141. These co-operate as before with the carriage rails 90 through anti-friction rollers but the construction provides for an extended run of the carriage without obstruction of the fan-fold sheet *d* by the side supports 140 of the stationary guide rails, these supports being spaced apart sufficiently to permit of a complete transverse 85 movement of the carriage without bringing the side edges of the fan-fold sheets into contact with said supports or posts. To accommodate the fan-fold sheets which ordinarily are continuous or extended strips, the table 93 is provided with a slot indicated at 142 and secured to said table behind the slot is an inclined paper deflector 143 over which the continuous fan-fold sheet or blank may be led up from the rear 90 of the machine, thence passing through the slot 142 and up at the front side of the table or paper receiving element 93. An ordinary severing device for severing the sections of the strip *d* is preferably arranged near the top of the table 93.

Various other modifications and changes will suggest themselves to those skilled in the art by which the principles of my invention may be adapted for use in connection with different kinds or forms of type-writing and particularly of commercial typewriting.

What I claim as new and desire to secure by Letters Patent, is,

1. In a typewriting machine, the combination of printing instrumentalities, a supporting frame therefor, a traveling paper holding means for holding the printing portion of the paper substantially vertical, and means for affording movement of the supporting frame horizontally away from the paper holding means entirely independently of the paper thereon.

2. In a typewriting machine, the combination of printing instrumentalities, a movably mounted support by which said instrumentalities are carried, a traveling paper carriage, and letter feeding devices for said carriage, said support being movable

horizontally away from said carriage in a direction substantially at right-angles to the vertical writing plane of the paper on said carriage.

5 3. In a typewriting machine, the combination of a set of type bars, a movably mounted support for said type bars, a traveling paper carriage for maintaining the printing portion of the paper in a substantially vertical plane, and escapement devices connected with said carriage, said support being movable forward by hand away from the paper and in a direction substantially at right-angles to the plane of the 10 paper.

4. In a typewriting machine, the combination of a collating plate constantly disposed in a substantially upright position, a set of front strike type bars, a frame on 20 which said type bars are mounted, step by step feeding devices for said collating plate, and bearings for said frame enabling it to be pulled forward away from said collating plate.

25 5. In a front strike typewriting machine, the combination of a rotary platen, a set of key operated type bars co-operative with the front face of said platen, a frame on which said type bars are mounted, and 30 roller bearings for said frame enabling it to be moved to carry the type bars away from a normal relationship with the platen.

6. In a front strike typewriting machine, the combination of a rotary platen, paper 35 guiding and controlling devices for maintaining and feeding the paper in a substantially vertical position across the printing face of said platen, a traveling carriage on which said platen is mounted, step by 40 step feeding devices for said carriage, a set of front strike type bars, a supporting frame therefor, and roller bearings for said frame enabling the frame to be pulled forward away from the printing face of the 45 platen.

7. In a front strike typewriting machine, the combination of a traveling carriage, a rotary platen thereon, pressure rollers co-operative with said platen, paper guiding 50 devices for constantly maintaining the paper in an upright position at the front side of said platen, line spacing devices for turning the platen step by step, a set of front strike type bars, a frame on which said type bars are mounted, and fore-and-aft guiding 55 devices on which said frame is movably supported so as to enable said frame to be pulled forward away from the printing face of the platen.

60 8. In a typewriting machine, the combination of a paper carriage movable transversely along fixed guides, and printing instrumentalities mounted in a frame that is movable toward and from the operator.

65 9. In a typewriting machine, the com-

bination of a paper carriage movable transversely along fixed guides, and printing instrumentalities mounted in a frame that is movable at right-angles to the movement of said paper carriage.

70 10. In a typewriting machine, the combination with a front strike printing mechanism, of a paper holder for supporting paper in an upright position in rear of said mechanism, and means for affording bodily movement of said mechanism away from said holder to provide a gap between the two for the convenient manipulation of the paper on said holder.

75 11. In a typewriting machine, the combination with a front strike printing mechanism, of a paper holder for supporting paper in an upright position in rear of said mechanism, and means for movably mounting said mechanism to enable it to be drawn forward bodily away from said paper holder.

80 12. In a typewriting machine, the combination with a front strike printing mechanism, of a paper holder for supporting paper in an upright position in rear of said mechanism, and roller bearings on which said mechanism is mounted.

85 13. In a typewriting machine, the combination with a front strike printing mechanism comprising type bars, printing keys and connections between said type bars and said keys, of a paper holder for supporting paper in an upright position in rear of said mechanism, roller bearings on which said mechanism in its entirety is mounted, and stop devices for limiting the to-and-fro movements of said entire mechanism on its 90 bearings.

95 14. In a typewriting machine, the combination with a front strike printing mechanism comprising type bars, printing keys and connections between said type bars and said keys, of a paper holder for supporting paper in an upright position in rear of said mechanism, roller bearings on which said mechanism in its entirety is mounted, and 100 detent devices for retaining said mechanism in any one of a plurality of predetermined positions to which it may be moved on its 105 bearings.

110 15. In a typewriting machine, the combination with a front strike printing mechanism comprising type bars, printing keys and connections between said type bars and said keys, of a paper holder for supporting paper in an upright position in rear of said mechanism, fixed trackways, and roller bearings connecting said mechanism as a 115 whole with said trackways.

120 16. In a typewriting machine, the combination with a front strike printing mechanism comprising type bars, printing keys and connections between said type bars and said keys, of a paper holder for supporting paper in an upright position in rear of said 125

- mechanism, rollers for supporting the whole of said mechanism, and fixed parallel trackways for said rollers. 60
17. In a typewriting machine, the combination with a front strike printing mechanism comprising type bars, printing keys and connections between said type bars and said keys, a frame on which said mechanism is mounted in its entirety, a support on 65 which said frame is movably mounted, and a paper holder for supporting paper in an upright position in rear of said mechanism, said paper holder being independent of said frame. 70
18. In a typewriting machine, the combination with a front strike printing mechanism comprising type bars, printing keys and connections between said type bars and said keys, a frame on which said mechanism is mounted in its entirety, fixed trackways, roller bearings between said trackways and said frame, and a paper holder mounted in rear of said printing mechanism independently of said frame. 75
19. In a typewriting machine, the combination of a frame member, a support on which said frame member is movably mounted, a set of key actuated type bars on said frame member, a paper holder for supporting paper in an upright position in rear of said type bars, and means for affording a movement of said frame member horizontally forward away from said paper holder to provide a gap or space to enable the 80 paper to be conveniently adjusted on said holder. 85
20. In a typewriting machine, the combination of printing instrumentalities, a movably mounted support by which said instrumentalities are carried, a traveling paper carriage, spring drum mechanism on said movable support, escapement devices on said movable support, and connections between said escapement devices and said carriage, said support being movable away from said carriage and said connections being extensible to prevent disconnection of said connections. 90
21. In a typewriting machine, the combination of a supporting frame, printing mechanism, ribbon mechanism, carriage motor mechanism, escapement mechanism, all of said mechanisms being mounted on said frame, a traveling paper carriage, connections between said carriage and said escapement mechanism, and means for affording movement of said supporting frame away from said carriage in a direction substan- 95
- tially at right-angles to the printing plane of the paper on said carriage. 100
22. In a typewriting machine, the combination of a supporting frame, printing mechanism, ribbon mechanism, carriage motor mechanism, escapement mechanism, all of said mechanisms being mounted on said frame, a traveling paper carriage, connections between said carriage and said escapement mechanism, means for affording movement of said supporting frame away from said carriage in a direction substantially at 105 right-angles to the printing plane of the paper on said carriage, and means for retaining said carriage in abnormal position on said frame. 110
23. In a typewriting machine, the combination of a movably mounted frame, a set of type bars thereon, a traveling paper carriage, escapement devices connected with said carriage, tabulating mechanism comprising stops on said carriage and co-operating stops on said frame, carriage releasing devices operative by said tabulating mechanism, and means for affording movement of said supporting frame away from said paper carriage to provide sufficient space to conveniently adjust the paper on said carriage. 115
24. In a typewriting machine, the combination of a movably mounted frame, a set of type bars thereon, a traveling paper carriage, escapement devices connected with said carriage, tabulating mechanism comprising stops on said carriage and co-operating stops on said frame, carriage releasing means operative by said tabulating mechanism, releasing means on said carriage operative independently of the tabulator controlled releasing means, and means for affording movement of said supporting frame away from said paper carriage to provide sufficient space to conveniently adjust the paper on said carriage. 120
25. In a typewriting machine, the combination of a platen, printing instrumentalities, a supporting frame therefor, and means for affording movement of the latter forward away from the front face of the platen in a direction substantially at right angles to the writing plane. 125

Signed at the borough of Manhattan, city of New York, in the county of New York, and State of New York, this 24th day of June, A. D. 1921.

MORRIS W. POOL.
